SZYMON JACHIMOVICZ, OF BERKELEY, CALIFORNIA.

VALVE MECHANISM FOR GAS-ENGINES.

No. 911,992.

Specification of Letters Patent.

Patented Feb. 9, 1909.

Application filed August 2, 1907. Serial No. 386,819.

To all whom it may concern:

Be it known that I, SZYMON JACHIMOVICZ, a subject of the Emperor of Russia, residing at Berkeley, in the county of Alameda and State of California, have invented new and useful Improvements in Valve Mechanism for Gas-Engines, of which the following is a specification.

This invention relates to improvements in the means for admitting air and gas for gas engines, and for exhausting therefrom.

The objects of the invention are, first, to actuate both the inlet and the exhaust valves by a single eccentric; second, to provide a simple means for regulating the mixture, both quantitatively, as to the amount admitted, and qualitatively, as to the proportion of air and gas and in both cases without throttling the gas supply; third, to provide simple means for maintaining the valve closed when starting the engine by compressed air; fourth, to provide an arrangement whereby, when using a comparatively small proportion of gas, the gas is admitted in a part only of the stroke, so that a portion of the charge is a comparatively rich mixture of gas and air, whereby a greater certainty of explosion is obtained; fifth, to provide means whereby the amount of air admitted may be proportioned to the quality of the gas used, so that when good gas is used more air can be admitted and less air when poor gas is used; sixth, to provide an arrangement by which adjustment of the ports for the air and gas, to reduce the amount of the fluid admitted may take place in a vertical and not in a horizontal direction, and whereby also the air shall be admitted above the gas and in a downward direction, thereby insuring as much as possible the complete mixture of the gas and air; seventh, to provide means whereby the control of the mechanism for admitting the air and gas shall entail as little work as possible upon the governor.

In the accompanying drawings, Figure 1 is a transverse section, of the admission end of a gas engine to which my improvement is applied; Fig. 2 is a detail sectional view of the valve chamber; Fig. 3 is a horizontal section of the same on the line 3—3 of Fig. 1; Fig. 4 is a diagrammatic view of one of the air ports and of a portion of the slide valve adjacent thereto; Fig. 5 is a similar view of the gas inlet; Fig. 6 is a view, similar to Fig. 1, of a modification of my invention as applied to an

old form of single acting gas engine; Fig. 7 is a broken longitudinal section of the same.

Referring to the drawing, 1 indicates the casing of the engine, having the inlet valve 2 and the exhaust valve 3, the latter operated by means of an eccentric 4, through a lug 19 on the ring 20 of the eccentric, a bell crank lever 5 and a link 6.

The inlet valve 2 is carried by a stem 7 connected to a union 8, which in its turn is connected to a stem 9 which is normally raised by means of a spring 10. Upon this union are pins 11, which are adapted to be engaged by a forked lever 12, pivoted at 13 on an extension 14 from the head of the valve box 15. The outer end of said lever is adapted to be engaged by a hooked lever 16 pivoted at 17 on the upper end of a pitman 18, connected to a lug 19 of the ring 20 of the eccentric 4. Said pitman is also connected by a link 21 with the same pivot as the lever 12. The hooked lever 16 is provided with a tail 22, which is engaged by two springs 23, 24, so as to normally maintain it in its operative position on the pitman. With the lever 12 is connected the rod 25 of a piston working in a dash pot 26 attached to a bracket 27 extending from the valve box 15. Adjustably attached to the extension 14 is a curved deflector 28 which is adapted to engage a nose 29 on the hooked lever 16. In the drawing, the pitman is shown in its lowest position and as it rises by reason of the rotation of the eccentric 4, the hooked end of the lever 16 engages the end of the lever 12 and thereby depresses the valve 2 admitting to the engine the mixture of gas and air. As the pitman continues to rise the nose 29 strikes against the deflector 28, causing the hook to be withdrawn from the end of the lever 12, whereupon the valve immediately rises under the action of the spring 10. As the pitman descends, owing to the continued rotation of the eccentric, the hook again returns to its normal position ready to engage the end of the lever 12.

The curved deflector 28 is automatically adjusted by a lever 31 which is connected by a link 32 to the governor 30, of the gas engine, so that the cut-off is automatically controlled by the governor according to the speed of the gas engine.

33 indicates the air inlet conduit and 34 the gas inlet conduit. The conduit 33 leads to a chamber 35 connected by passages 36

with the interior of the valve box 15. In like manner, the conduit 34 leads to a chamber 37. Between the chambers 35 and 37 is an annular chamber 38 having upper and lower ports 39 and 40 extending respectively obliquely upwards and downwards from the chamber to the interior of the valve box. The two ports 39, 40, are made oblique so as to direct the current of air at such an angle as to effect the most perfect mixture with the gas.

Within the valve box slides the valve 41 which is attached to a sleeve 42 around the valve stem. Said sleeve and the valve connected therewith reciprocate always in unison with the inlet valve, but can be turned around said stem by means of a slot 43 formed in said sleeve, into which extends a pin 44 from a collar 45, connected with a lever 46 connected through the deflector shaft with the governor 30 of the engine, so that the valve is turned automatically in accordance with the speed of the engine. The passage of the air is controlled by a ring 47, which can be moved by rods 48 over either of the ports 39, 40, to regulate the size of said ports. These rods can be operated in any convenient way, as by nuts, one of which is shown upon one of said rods in Fig. 6.

The valve 41 is formed with a hub 50 attached to the sleeve 42 and flaring outwards at the top, as shown at 51, being then formed into a flange 52, which acts as a slide valve over the upper air ports 39. It is also formed with radial webs 53 on which are formed the lower slide valve 54 which slides over the gas inlet ports 55 said slide 54 being undercut on its upper surface so as to form a small chamber in which any deposits of tar, or like matter can be received, to prevent the valve sticking. The upper slide 52 is in the form of a narrow cylinder, so as to conform to the arrangement of the upper air ports, but the lower slide 54 has its upper edge formed in a series of inclines conforming to the spiral form of the gas inlets 55. This arrangement is shown diagrammatically in Fig. 5 in which the full lines show the position for a maximum admission and the dotted lines for minimum admission. It will readily be seen that, in the former position, the gas inlet ports are opened as soon as the valve begins to move downwards and therefore a maximum admission of gas is obtained, but when the valve has been moved to the position shown in dotted lines, the valve descends a considerable distance, before the gas inlet ports begin to be uncovered and said inlet ports remain uncovered for a comparatively short time, so that in the latter position the proportion of gas to air is reduced.

When the gas engine is to be started by the use of compressed air, it is necessary to maintain the inlet valve closed otherwise the compressed air would escape, and to accom-

plish this result, there is provided a lever 57 adapted to be operated by means of a link 58, the end of said lever when so operated being moved to such a position that it interferes with the hook 16 when in its lower position and prevents the latter engaging the end of the lever 12 to open the inlet valve.

It will be observed that the inlet and exhaust valves are both operated from a single eccentric. This I am enabled to accomplish by means of the special arrangement of the two lugs 19, 19', the bell crank lever 5, and the links 6 and 18.

In Figs. 6 and 7 is shown a modification of my invention applied to an old style of engine. In this modification also, 2 indicates the inlet valve and 3 the exhaust valve, and, as before, there is a sleeve 42 movable with the valve stem and rotatable on said stem, said sleeve carrying a slide piece. In the present instance, there is shown a handle 60 for so turning said tube. It may be, however, also turned from the governor in the same way as in the former modification. The general arrangement of the valve ports and the slide is similar to that in the first modification, except that the intermediate chamber 38 is now dispensed with, and the air is admitted direct from the air chamber 35. Instead of the valve being operated by an eccentric, as in the first modification, it is now operated by means of a cam 61 and this cam should be of such form that the valve shall not remain at rest for any appreciable portion of the stroke when it is opened to its full extent. By providing a cam of this form it is possible to reduce as much as may be desired, the amount of gas admitted. If the cam were of such a form that, for a considerable part of the stroke, the valve remained stationary when opened, then during this part of the stroke, when the valve so remained stationary, it would not be possible to make any variation in the amount of gas admitted. It will also be observed that by this construction of air and gas inlets, so regulated, while the air is admitted during the whole of the stroke of the valve, the gas, when admitted for a part only of the stroke, is admitted wholly in the middle portion of said stroke; that is to say, in the latter case, the air is admitted both before and after the gas is admitted. The proportion of the part of the stroke during which the gas is so admitted in the middle of the stroke will vary with the proportions of the mixture desired, and is obtained by turning the slide valve from the governor. But in all cases, except when the gas is admitted during the whole stroke, the admission of the gas is confined to the middle part of the stroke. The advantage of this arrangement is, that thereby the ignition is much more certain and effective when a very small amount of gas is admitted. In prior devices, when a comparatively small

quantity of gas was admitted during the whole of the stroke the result would be that, the gas being uniformly mixed with the air, the explosion would be very weak, and in some cases would not take place at all. With 5 the present arrangement, even though no more gas be admitted, yet the ignition is much more certain, by reason of the fact that the gas is mixed with a part only of the air, which mixture is between two layers 10 of comparatively pure air. In order, however, to obtain the benefit of this arrangement it is necessary that the ignition device 15 should be arranged in proximity with this comparatively rich middle layer of the mixture, that is, it should be placed as near as possible to the middle of compression chamber where this layer of comparatively rich mixture will be found before ignition.

20 I claim:—

1. In a gas engine, the combination with the body of the engine, of a shaft, an eccentric upon said shaft, a ring on said eccentric having two lugs, a lever connected to one of 25 said lugs and to the engine frame, means for opening the exhaust valve by the movement of said lever, a rod connected to the other lug of the eccentric, a hooked member carried by said rod and adapted to engage the lever 30 which opens the inlet valve, means controlled by the governor for breaking said engagement, a spring for closing said valve, a slide valve movable with said inlet valve but rotatable around its stem, a valve box having 35 air ports arranged in planes at right angles to the axis of said box and gas ports spirally arranged, said slide valve having edges adapted to cover said air and gas ports, and means controlled by the governor to rotate said 40 slide valve, whereby the gas may be admitted only after the air has been admitted.

2. In a gas engine, a mixing chamber having circumferential air ports and inclined gas ports, a slide valve in said mixing chamber 45 reciprocating with the inlet valve and having a correspondingly shaped edge adapted to cover said ports, means controlled by the governor for rotating said slide-valve relatively to said ports, whereby the opening of 50 the gas ports by said slide valve may be retarded and their closing advanced relatively to the opening and closing of the air ports which remain constant.

3. In a gas engine, the combination of a 55 valve box having air and gas ports, the latter being arranged obliquely, an inlet valve, a slide piece movable with said inlet valve, but rotatable with reference to said ports, and means for so rotating said slide piece, that 60 the gas may be admitted only after the air has been admitted, substantially as described.

4. In a gas engine, the combination, with the body of the engine having a mixing chamber and a compression chamber, an inlet valve between the mixing chamber and the compression chamber, air and gas ports in the wall of the mixing chamber, means reciprocating with the inlet valve for opening and closing said ports, means for rotating one 65 of the said elements, the said wall and the closing and opening means, relative to the other, said ports and said closing means being conformed to vary the time of opening of said ports by said reciprocation, substantially as described.

In testimony whereof I have hereunto set my hand in the presence of two subscribing witnesses.

SZYMON JACHIMOVICZ.
